CLAIM

We claim the ornamental design for a cigarette manufacturing machine, as shown and described.

DESCRIPTION

FIG. 1 is a front-top-left side perspective view of a cigarette manufacturing machine;

FIG. 2 is a rear-top-right side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines shown in the drawings depict portions of the cigarette manufacturing machine that form no part of the claimed design.
